Primary Examiner — Richard Edgar*Assistant Examiner* — Jessica Ruth Grable(74) *Attorney, Agent, or Firm* — Jose Cherson Weissbrot(57) **CLAIM**

The ornamental design for a TV cabinet, as shown and described.

DESCRIPTION

FIG. 1 is a top front right perspective view of a TV cabinet, showing my new design;

FIG. 2 is a bottom rear left perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken line show parts of the TV cabinet that form no part of the claimed design.

1 Claim, 8 Drawing Sheets(56)
